CLOCK

Theodore A. Granroth, Elmhurst, Ill., assignor to
Motorola, Inc., Franklin Park, Ill., a corporation
of Illinois

Filed May 20, 1963, Ser. No. 281,693
4 Claims. (Cl. 58—50)

This invention relates to clocks, and more particularly to an improved clock having provision for illumination of the face thereof.

It becomes desirable in certain types of clocks, such as are used in sleeping rooms (e.g. alarm clocks and clock radios), to provide some means for rendering the clock sufficiently visible in a darkened environment to enable an observer to tell the correct time. One method of doing this is to coat the hands and the numbers of the clock with phosphorescent chemicals. This is unsatisfactory in certain respects because, during a long period of darkness, such chemicals may lose much of their stored energy, decreasing the brightness of the hands and numbers. Another approach to the problem is to coat the hands and numbers with radioactive material. Because of the radiation associated with such chemicals, however, the general public is often hesitant to purchase such a device. Another possibility is to light the clock face itself by means of an electric light. In general, however, such lights utilize too much power to be operated continuously, especially when the whole face is to be lighted. Consequently, an on-off switch must be provided with the attendant inconvenience and increased cost to the consumer.

Accordingly, it is an object of this invention to provide improved, non-chemical lighting for the face of a clock.

Another object of the invention is to provide a clock having an evenly lighted face visible in a darkened environment and apparently unlighted when viewed in a lighted environment.

Still another object of the invention is to provide a clock having a continuously electric lighted face and utilizing a minimum amount of current.

A feature of the invention is the provision, in a clock, of a translucent face and a disk shaped light conductor having a frosted surface and being mounted behind the face with a neon bulb mounted on the edge of the light conductor and lighting the light conductor to silhouette the hands of the clock.

Another feature of the invention is the provision of a light conductor constructed of frosted Plexiglas, and the further provision of an unfrosted portion on the light conductor near the light source for even distribution of light. The available light can be increased by utilizing a reflector behind the light conductor, which reflector has a non-reflecting portion behind the unfrosted portion of the light conductor for even distribution of light.

Still another feature of the invention is the provision of a translucent clock face with a reversed second face printed on the back side of the clock face and having opaque figures. A light conductor is provided behind the second face and silhouettes the hands and the figures of the second face at night.

In the drawings:

FIG. 1 is a perspective view of a clock radio incorporating the invention;

FIG. 2 is a view of the appearance of the clock shown in FIG. 1 when viewed in a darkened environment;

FIG. 3 is an exploded view of the clock shown in FIG. 1;

FIG. 4 is a perspective view of a clock radio incorporating a second embodiment of the invention; and

2

FIG. 5 is an exploded view of the clock shown in FIG. 4.

In accordance with the invention, a clock is provided with a translucent face disposed behind the indicator hands thereof. A substantially disk shaped frosted Plexiglas light conductor is mounted behind the translucent portion of the clock face. This light conductor has a portion extending from the periphery thereof which portion has a mounting recess in which is disposed a neon bulb. The neon bulb may be connected across the line and in series with a resistor to draw a very small amount of current. When the bulb lights, the light conductor transmits light over the rear of the clock face silhouetting the hands of the clock.

One embodiment of the invention utilizes a second clock face painted on the rear side of the translucent clock face, which second clock face is silhouetted by the light conductor. Another embodiment of the invention utilizes an opaque ring containing transparent figures which are lighted by the light conductor. Both embodiments of the invention utilize a light conductor of frosted Plexiglas and having an unfrosted section adjacent the neon bulb to permit an even distribution of light across the clock face. When the clock face is viewed in a lighted environment, the light produced by the neon bulb is insufficient to off-set the effect of the reflected environmental light from the translucent clock face. Accordingly, the silhouetting effect does not take place until the environment becomes darkened sufficiently for silhouetting to occur.

Referring now to FIG. 1, there is shown a clock radio 11 having a control panel 13 with appropriate controls thereon and further having a clock mounted therein. The clock includes a second hand 15, a minute hand 17, an hour hand 19 and an alarm setting indicator 21. The clock also includes appropriate figures 23 imprinted about the face 25 in the usual manner.

Face 25 contains a translucent portion 27, which may be translucent vinyl, or vacuum metalized butyrate. Metalized butyrate presents a metallic appearance when viewed in a lighted environment but is translucent and will transmit light which will be visible to an observer when reflected light becomes low enough.

Referring now to FIGS. 2 and 3, a frosted Plexiglas light conductor is mounted behind face 25. Conductor 29 has a pair of openings 31 formed therein to permit passage of the alarm and clock setting controls therethrough. In addition, a central opening 33 is provided for the drive post of the hands. Light conductor 29 is substantially disk shaped and has an extension 35 at the periphery thereof. Extension 35 includes a recess 37 in which a neon bulb 39 is mounted. Bulb 39 may be lighted by connection in series with a resistor across the line source. The area 41 adjacent extension 35 is unfrosted to permit a more even diffusion of the light throughout conductor 29, and avoid a concentration of light adjacent light bulb 39. A shield 43 of opaque material such as aluminum foil surrounds extension 37 to permit lighting only through light conductor 29.

With the components in place and when viewed in a darkened environment, light conductor 29 will cause translucent section 27 to glow with a soft light, silhouetting the hands 15, 17, 19 and 21. In addition a series of opaque figures 45 are disposed on the reverse side of translucent section 27. Figures 45 comprise a smaller second clock face which is silhouetted when the glow from light conductor 29 is visible through translucent portion 27. When viewed from a lightened environment, only the larger exterior clock face will be visible. FIG. 2 shows the appearance of the second clock face and the silhouetted hands as viewed from a darkened environment.

Conductor 29 permits the use of neon bulb 39 which may be a very low light source. Nevertheless, the efficient dissemination of light behind the clock face 25 permits bulb 39 to provide a soft glow over the entire face when viewed from a darkened environment. In addition, because a small neon bulb 39 may be used, low current drain takes place. This permits the bulb to be kept on at all times, eliminating the need for a switch. Replacement will seldom, if ever, be needed because such neon bulbs are of very long life. Clock hands 15, 17, 19 and 21 may of course, be driven by a motor assembly 47. A glass cover 49 protects the clock face and hands.

Referring now to FIGS. 4 and 5, a second embodiment of the invention is shown. In the clock radio 50, of FIGS. 4 and 5, the clock face is comprised of a translucent section 51 and a ring 53 of opaque vinyl containing transparent numbers 55. Light conductor 29 is backed by a reflector 57. The portion 59 of reflector 57 behind the unfrosted portion 41 of light conductor 29 is blacked out to prevent excessive brightness at the light source. Portion 59 may be slightly larger than unfrosted portion 41 of light conductor 29 to present an even distribution over the face of the clock. When viewed at night, hands 15, 17, 19 and 21 will be silhouetted against translucent portion 51, and numbers 55 will pass light reflected from reflector 57 so that the numbers are visible in the dark. Here again, when the environmental light is sufficiently strong, the effect of neon bulb 39 will be unnoticeable.

It may therefore be seen that the invention provides a clock wherein improved non-chemical lighting is provided. The face of the clock is evenly lighted in a darkened environment and apparently unlighted in a lighted environment, whereas in reality continuous lighting exists with minimum current drain.

I claim:

1. A clock having provision for illumination of the face thereof, including in combination, a plurality of opaque indicator hands, a clock face disposed behind said indicator hands and including a translucent portion adapted to silhouette said hands when lighted, a substantially disk shaped light conductor having a frosted surface and being mounted behind said translucent portion of said clock face, a bulb retaining extension on the periphery of said light conductor, a neon bulb secured in said bulb retaining extension and supplying light to said light conductor for lighting said translucent portion of said clock face to silhouette said hands, said frosted surface of said light conductor having an unfrosted portion adjacent said bulb to even the intensity of the light over the entire light conductor, whereby the position of said hands is observable from a darkened environment.

2. A clock having provision for illumination of the face thereof, including in combination, a plurality of opaque indicator hands, a clock face disposed behind said indicator hands and having a first set of clock figures thereon visible in a lighted environment, said clock face further having a translucent portion inwardly of said first set of clock figures adapted to silhouette said hands when lighted, said translucent portion including an opaque second set of clock figures on the reverse side thereof to be silhouetted when said translucent portion is lighted, a substantially disk shaped light conductor having a frosted surface and being mounted behind said translucent portion of said clock face, a bulb retaining extension on the periphery of said light conductor, a neon bulb secured in said bulb retaining extension and supplying light to said light conductor for lighting said translucent portion of said clock face to silhouette said hands and said second

set of figures, said frosted surface of said light conductor having an unfrosted portion adjacent said bulb to permit even distribution of light throughout said light conductor, whereby the position of said hands and said second set of clock figures is observable from a darkened environment, said neon bulb being of a value to render said translucent portion substantially opaque in a lighted environment.

3. In a radio receiver, a clock having provision for illumination of the face thereof including in combination, a plurality of opaque indicator hands, a clock face disposed behind said indicator hands, said clock face having a vacuum metalized translucent portion in the center thereof adapted to silhouette said hands when lighted, said translucent portion including opaque clock figures painted on the reverse side thereof to be silhouetted when said translucent portion is lighted, a substantially disk shaped light conductor having a frosted surface and being mounted behind said translucent portion of said clock face, a bulb retaining extension on the periphery of said light conductor and integral therewith, a neon bulb secured in said bulb retaining extension and supplying light to said light conductor for lighting said translucent portion of said clock face to silhouette said hands and said figures, light shield means surrounding said extension and permitting emission of light only through said light conductor, said frosted surface of said light conductor having an unfrosted portion adjacent said bulb to permit even distribution of light throughout said light conductor, whereby the position of said hands and said clock figures is observable from a darkened environment, said neon bulb being of a value to render said translucent portion substantially opaque in a lighted environment.

4. A clock having provision for illumination of the face thereof, including in combination, a plurality of opaque indicator hands, a clock face disposed behind said indicator hands, said clock face having a substantially circular translucent portion in the center thereof adapted to silhouette said hands when lighted, and further having an opaque annular band surrounding said translucent portion and having transparent clock figures thereon, a substantially disk shaped light conductor having a frosted surface and being mounted behind said clock face, a bulb retaining extension on the periphery of said light conductor, a neon bulb secured in said bulb retaining extension and supplying light to said light conductor for lighting said translucent portion of the said clock face to silhouette said hands and illuminate said figures, said frosted surface of said light conductor having an unfrosted portion adjacent said bulb to permit even distribution of light throughout said light conductor, light shield means surrounding said extension and permitting emission of light therefrom only through said light conductor, a reflector mounted behind said light conductor for reflecting light to said clock face, said reflector including a non-reflecting portion located behind said unfrosted portion of said light conductor, whereby the position of said hands and said clock figures is observable from a darkened environment, said neon bulb being of a value to render said translucent portion substantially opaque in a lighted environment.
